UNITED STATES PATENT OFFICE.

CLARENCE J. RODMAN, OF WILKINSBURG, AND MAX HECHT, OF PITTSBURGE, PENNSYLVANIA.

PROCESS AND APPARATUS FOR RECONDITIONING MINERAL OILS.

Application filed November 11, 1925 Serial No. 68,300.

The present invention relates to the treatment of mineral oils, and particularly to the reconditioning of oils which, for example, have been taken from electrical equipment, such as transformers, circuit breakers, and the like, but the invention is also applicable to the treatment of other used or impure mineral oils.

According to the present invention, it is proposed to subject the impure or used oil to a process of purification under such conditions as to substantially retard oxidation of the oil during treatment and in such manner as to remove water, dissolved gases and volatile impurities, and to then remove other impurities such as unsaturates, resinous compounds, acidic compounds, oxidation products, carbon, sludge, sediment, etc.

According to the present invention, it is proposed also to heat the oil, to a limited extent, under conditions which will prevent overheating thereof and to utilize heat which would otherwise be wasted for preheating the oil prior to its introduction into the reconditioning apparatus.

The nature and objects of the invention may be readily understood by reference to the accompanying drawings which show more or less diagrammatically a preferred embodiment of our invention, but it will be understood that we do not confine ourselves to the use of the particular apparatus shown or to the specific manner of practicing the invention, as various changes in construction and modes of operation are contemplated within the spirit of our invention.

In the drawings the figure is a schematic view of the entire apparatus.

In the drawings, 2 designates an oil supply pipe through which impure or used mineral oils to be reconditioned are introduced into the apparatus. The oil to be treated may, for instance, be an oil which has been used in a transformer or in a circuit breaker or other electrical equipment. Oil may be supplied to pipe 2 from any suitable source through any preferred method of feed, either by gravity or otherwise.

Pipe 2 leads through the top 3 of a tank 4 having a bottom 5 and having a cylindrical inner wall 6 spaced inside thereof, and having a perforate extension 7 at its lower end. This might, for example, be formed of fine mesh screen. Pipe 2 within the tank 4 terminates

at the bottom 8 of a suitable heater designated 9. In its preferred form, this heater comprises a suitable chamber divided by partitions 10 into a plurality of relatively narrow columns. In each partition there is preferably an electric heating element, so that each partition, in effect, is a thin flat heating surface. These heating elements may be supplied with current through conductors indicated at 11.

The arrangement of the heater is such that the oil entering the lower portion 8 of the heater rises therethrough into the main chamber of the heater where it rises in thin films over the surface of the heating units, which units are in close proximity to each other. It is preferred that the partitions or heaters are at such distance as to permit a maximum heat absorption without overheating any part of the oil, thereby minimizing oxidation or decomposition resulting from heating. It will be understood, however, that the oil may be heated and the stream of oil broken up in the vacuum chamber to release easily volatile substances, gases and water, in other ways.

Leading from the upper part of the tank 4 is a pipe 13 which preferably leads into a heat exchanger 14 arranged about the pipe 2. In the lower part of the heat exchanger 14 is a drain pipe 15 through which condensates may be removed. Leading from the heat exchanger 14 is a pipe 16 that connects with a suitable vacuum pump designated 17 and driven by a motor 18. The pump 17 maintains the pressure in the tank 4 at a suitably reduced pressure for the effectual separation and removal of water, gases, volatiles, etc., at the desired temperature, the pressure being preferably maintained at substantially 2.5 pounds per square inch absolute, and the temperature is preferably maintained at about 150° Fahrenheit.

Suspended from the walls 6 within the tank 4 and below the heater 9 are a plurality of deflectors 19 which are preferably of the alternately reversed cone type. During the operation of the apparatus, oil, which passes through the heater 9, froths over the top thereof and falls onto the first of the deflectors 19. It flows successively from one deflector to another in thin films, so that any gases which remain in the oil can be readily released. From the lowermost deflector 19 the oil falls into the bottom of the tank where it collects.

Leading from the bottom of the tank 4 is a pipe 20 connecting with a suitable pump, preferably a centrifugal or other rotary type of pump, 21. The pump 21 may also be driven by motor 18. Leading from the outlet side of the pump 21 is a pipe 22 that connects with the receiving end of a reaction tank 23. The reaction tank 23 is preferably vertically disposed, and has a conical bottom 24 which may be drained by a sludge cock 25. It may have a removable cover 26, and near the top thereof is an outlet pipe 27. Pipe 22 preferably discharges close to the conical bottom of the tank whereby agitation and thorough mixing of an adsorptive compound or substance is secured. At the same time, the tank has sufficient volume so that the flow of oil therethrough is very gradual and quiet in the upper part thereof. This provides for an initial turbulent introduction of the oil with a subsequent quiescent period of reaction. The outlet pipe 27 preferably connects with a manifold 28.

Leading from the manifold 28 are branch pipes 29 connecting with filters 30. Each pipe 29 preferably has a valve 31 therein, so that the flow of oil from the manifold to any filter may be controlled at will.

Filters 30 preferably include an outer casting 32, a base 33 and an inner porous shell 34, the inner shell 34 being spaced from the outer shell 32. Pipes 29 lead to the space 35 between the inner porous shell and the outer casing. Leading from the central chamber 36 within the porous shell 34 of each filter is a pipe 37. Each of the pipes 37 has a valve 38 therein and these pipes connect with a manifold 39. From manifold 39 the oil is preferably conducted through a heat exchanger 40 also located about the pipe 2. From the heat exchanger 40 the oil may be conducted through pipe 41 to a suitable collecting or storage reservoir.

While we have described one form of filter, we are not necessarily confined to the particular form shown, as any device for this purpose which may be found suitable, may be substituted. We do prefer, however, that the filter plate, such as the shell 34, be of a baked porous material whose porosity may be determined by the character of the material used. With such a material there can be no danger of contamination of the oil with particles of lint, suspended or soluble filter material, or other substance, as might result with the use of other types of filters.

As the oil is withdrawn from the bottom of tank 4 through pipe 20, it is desirable to introduce a compound into the oil. For this purpose we have shown a container 43 having a proportional feeder 44 of any preferred type at the bottom thereof, this feeder being suitably driven, preferably by a drive connection, such as belt 45 from the motor 18. With such an arrangement the speed of the feed device may be in accordance with the speed of the

pump 21. The proportional feeder introduces dry partially evacuated adsorptive material down a pipe 46 into the pipe 20. A deflector 46^a is preferably provided in pipe 20 adjacent the terminal of pipe 46 so as to agitate the oil in the pipe 20 at this point to cause it to more readily mix and carry away the dry adsorptive compound or substance. 70

The air-tight container 43 may have a pipe at 47 terminating within the tank at 48 so that the contents of the container 43 will be subjected to the same partial vacuum maintained in the tank 48. This prevents any appreciable amount of air from being introduced into the oil through the proportional feeding device, and tends to remove any contained gases or air from the adsorbent material. 75

In the practice of the invention, the partially warmed or preheated oil enters the heating means for the initial stage of its purification. It is well known that if the oil is overheated, especially in the presence of oxygen, undesirable decomposition will result. During the practice of the present invention, 90 any such undesirable results are eliminated.

The incoming oil, in passing through the heater, is maintained in a state of agitation, a turbulent motion being imparted thereto by the heating of oil by the parallel heaters under the maintenance of conditions of partial vacuum in the tank 4. This agitation is increased by the combined ebullition, degasification and vaporization of contained impurities. The effective heating of the oil is 100 thus effected without chemical reactions of a destructive or harmful nature. 95

Under the conditions in which the oil is heated, moisture mechanically held or dissolved in the oil, dissolved gases, such as air, oxygen, nitrogen, light hydro-carbon gases and volatiles, are continuously eliminated from the oil. These vapors and gases are continuously removed by the vacuum pump 17, so that the oil is thoroughly evacuated at this 105 stage of the process. Some of these vapors condense in the heat exchanger 14 from which they may be removed.

The purpose of the perforate screen 7 is to reduce, to a minimum, the loss of finely divided or atomized oil, this screen serving to obstruct the passage of such oil particles to the vacuum pump. 115

The deflectors 19 are of such a length and number as to effect a thorough dehydratation and degasification, and volatilization of undesirable constituents before the oil finally drains into the bottom of the tank. 120

As the evacuated or dehydrated oil from which the undesirable volatiles have been removed passes out the pipe 20, a dry adsorptive compound or substance is supplied thereto from the container 43 as previously described, and is also evacuated as hereinbefore explained by the withdrawal of con- 125

tained gases therefrom through the pipe 47. An evacuated adsorbent is thus introduced into an evacuated oil. This dry material is a desiccated adsorptive compound or substance 5 having a high capacity or affinity for impurities contained in the oil. This compound or substance may consist of an activated or prepared charcoal, a filter clay, silica gel, or a suitable combination of these or similar substances in suitable proportions. We prefer to use an earth substance such as bentonite, or a char, particularly a char especially intended for filter purposes, or a combination of the two.

16 This desiccated adsorptive substance is thoroughly mixed into the oil by the action of the centrifugal pump 21. As the oil flows through the reaction chamber 23, the desiccated substance will combine with the impurities. These impurities are recognized as unsaturates, resinous compounds, acidic compounds, oxidation products, etc. As previously suggested the oil is thoroughly agitated in the bottom of the reaction chamber, while 25 it later passes through a zone of quiescent reaction. The time of reaction is sufficient to fully enable the desiccated adsorptive substance to combine with impurities. The reaction is more rapid due to the evacuation of 30 gases from the adsorbent prior to its introduction into the oil. Both condensed moisture and gases are removed from the cell spaces, and the total area of the surfaces are thereby available for the reactions which ensue. The adsorbent reactions are both more rapid and complete due to the greater affinity 35 of such treated adsorbent with oil which has been first heated in a vacuum.

40 The oil flowing from the reaction tank then passes through the filters. The filters serve to remove the finely divided suspended particles of desiccated adsorptive substance, together with such impurities as they have collected, while the reconditioned oil flows 45 through the filters and into the pipe 39. From pipe 39 the oil, which is still heated, flows through the heat exchanger 40 to further heat the used or impure oil passing 50 through pipe 2 and then the reconditioned oil may be conveyed through pipe 41 to any suitable collecting vessel.

55 As the oil containing the finely divided desiccated adsorptive substance passes through the filter, the particles of earthy material in the oil collect on the filter plate 34 and produce a mat which serves to effectively remove finely divided particles in the oil. In other words the desiccated adsorptive substance also aids the efficiency of the filter.

60 With the arrangement of filter shown, one or more filters can be idle by the closing of the valves leading thereto, while the other filters remain active. This permits of the cleaning or repair of one or more filters while the other 65 filters are in operation, adapting the process

to a continuous method of operation. Obviously, however, we are not confined to any particular arrangement or type of filters.

It will be apparent that the operation is carried out under conditions which preclude 70 oxidation of the oil as air is excluded until the oil has been completely reconditioned and cooled. By reason of the adsorptive material having been evacuated prior to its introduction into the oil, it has a greater affinity 75 for the impurities in the oil. Because of the fact that the oil has been evacuated and the water and the light volatiles removed therefrom, the evacuated adsorptive material will have a greater affinity for the impurities remaining in the oil, such as resinous compounds, unsaturates, etc., and the adsorptive is not spent in removing water or light hydrocarbons. Therefore, less adsorptive material 80 need be used and the time for reaction is reduced to the minimum. This permits the size of the apparatus to be reduced and makes it particularly adaptable for small installations.

85 The term "desiccated adsorptive substance" as herein used denotes any well known or suitable finely-divided desiccated substance or compound that may be introduced into the oil and which has an adsorptive affinity for the recognized impurities in 90 the oil, but which is not dissolved thereby. The term "dehydrated" as used in the present specification and claims with reference to the oil, means anhydrous, as do the terms dry and 95 desiccated, as used in connection with the adsorptive compounds.

100 We claim as our invention:

1. A method of reconditioning electric insulating mineral oil which comprises first evacuating the oil, then introducing an evacuated adsorbent into the oil and while maintaining the oil out of contact with atmospheric gases and then filtering the oil to remove the adsorbent while maintaining it out 105 of contact with atmospheric gases.

110 2. A method of treating mineral oil used for electrical insulation purposes which comprises evacuating the oil, introducing into the oil after it has been evacuated an anhydrous adsorbent which has also been partially evacuated and while maintaining the oil out 115 of contact with atmospheric gases and water, and then filtering the oil to remove the adsorbent, the oil being filtered substantially out of contact with atmospheric gases.

120 3. A method of treating electrical insulating mineral oil which consists in introducing partially evacuated adsorbent into an evacuated oil and then filtering the oil, the process being effected out of contact with water and atmospheric gases.

125 4. A method of reconditioning electric insulating mineral oil, which consists in first removing water and contained gases from the oil, then introducing an evacuated adsorptive 130

material into the oil that has been thus treated, whereby the maximum adsorptive properties of the desiccated material are spent in the removal of other impurities, then filtering the oil to remove the spent adsorptive material, the oil being kept free of contact with atmospheric gases and moisture during the process.

5. A method of reconditioning electric insulating mineral oil, which comprises heating the oil while under a partial vacuum and out of contact with atmospheric gases, whereby dissolved moisture, gases and low boiling impurities are driven off from the oil, introducing a desiccated adsorbent into the oil so treated and while maintaining the oil out of contact with atmospheric gases, and then filtering the oil to remove the adsorbent while maintaining it out of contact with atmospheric gases.

10. A method of reconditioning oils used for electrical insulating purposes, which consists in rendering the oil anhydrous and free of gases by heating it in a partial vacuum, then adding a dry adsorptive substance having an affinity for unsaturates, resinous constituents, acidic compounds and oxidation products, and then filtering the oil, the process being effected under conditions which preclude oxidation of the oil or prevent moisture from coming into contact therewith.

15. A method of reconditioning electrical insulating oil, which consists in dehydrating the oil by heating the same at sub-atmospheric pressure in a confined chamber which precludes oxidation of the oil or the absorption of atmospheric moisture, then mixing a dry adsorptive compound therewith and allowing the same to combine with impurities in 20 the oil, and then filtering the oil, these steps also being effected while maintaining the oil free of contact with atmospheric gases.

25. A method of reconditioning electrical insulating oil, which consists in heating divided streams of oil in a partial vacuum, flowing the heated oil over a deflector plate while under a partial vacuum, collecting the oil so treated, then introducing an evacuated adsorptive substance into the oil, and thereafter filtering the oil, the oil being excluded from contact with air and water during the process.

30. A method of reconditioning electrical insulating oil, which consists in heating the oil in a chamber from which air is excluded, flowing the heated oil over deflectors within the chamber, withdrawing vapors and gases from the chamber, removing the heated oil from the chamber, mixing an evacuated adsorbent substance therewith, and filtering the oil, the oil being confined against exposure to

atmospheric gases and moisture during the entire process.

35. A method of reconditioning electrical insulating oil, which consists in introducing the oil into a heater within a chamber from which air is excluded, heating the oil in the heater, flowing the hot oil over a deflector in said chamber, withdrawing gases and vapors from said chamber, circulating such gases and vapors about the incoming supply of oil to thereby preheat the oil before it passes into the heater, withdrawing the heated oil from the bottom of the chamber, mixing a desiccated adsorptive with the oil, filtering the oil, and passing the filtered oil through a heat 75 exchanger associated with the incoming oil supply, whereby the treated oil also serves to partially preheat the untreated oil entering the heater, the oil being confined against exposure to atmospheric gases during the 80 entire process.

40. Apparatus for reconditioning electrical insulating oil, including a tank, means for withdrawing gases from the tank, a heater within the tank, an oil supply for delivering oil to the heater, deflectors in the tank below the heater for receiving the oil therefrom, means for withdrawing oil from the bottom of the tank, enclosed means for introducing an evacuated adsorbent substance into the 90 oil upon its removal from said tank, and enclosed means for filtering the oil.

45. Apparatus for reconditioning electrical insulating oil including means for dehydrating and degasifying the oil and removing 95 volatilizable impurities therefrom, means for supplying a desiccated adsorptive substance to the oil after it flows from the first named means, and means for filtering the oil to which the desiccated adsorbent substance has 100 been supplied, the apparatus being closed against exposure of the oil to the atmosphere.

50. Apparatus for reconditioning electrical insulating oil, including means for heating, degasifying and dehydrating the oil, a reaction tank, means for removing dehydrated oil from the first named means into the reaction tank, means for introducing an evacuated adsorbent material into the oil before it flows into the reaction tank and after it leaves the first named means, and filtering means connected with the reaction chamber, said apparatus being substantially air-tight to prevent the oil being treated from coming into contact with air.

55. In testimony whereof we have hereunto set our hands.

CLARENCE J. RODMAN.
MAX HECHT.
